CLAIM

The ornamental design for a suspended utensil storage system, as shown and described.

DESCRIPTION

FIG. 1 is a perspective view of a suspended utensil storage system.

FIG. 2 is a front elevation view of a utensil tray of the suspended utensil storage system;

FIG. 3 is a rear elevation view of the utensil tray of the suspended utensil storage system;

FIG. 4 is a right side elevation view of the utensil tray of the suspended utensil storage system;

FIG. 5 is a left side elevation view of the utensil tray of the suspended utensil storage system;

FIG. 6 is a top plan view of the utensil tray of the suspended utensil storage system;

FIG. 7 is a bottom plan view of the utensil tray of the suspended utensil storage system;

FIG. 8 is a front elevation view of a debris collector tray of the suspended utensil storage system, the rear elevational view being a mirror image thereof;

FIG. 9 is a right side elevation view of the debris collector tray of the suspended utensil storage system;

FIG. 10 is a left side elevation view of the debris collector tray of the suspended utensil storage system;

FIG. 11 is a top plan view of the debris collector tray of the suspended utensil storage system;

FIG. 12 is a bottom plan view of the debris collector tray of the suspended utensil storage system;

FIG. 13 is another perspective view of the suspended utensil storage system;

FIG. 14 is a front elevation view of the suspended utensil storage system, the rear elevational view being a mirror image thereof;

FIG. 15 is a right side elevation view of the suspended utensil storage system;

FIG. 16 is a left side elevation view of the suspended utensil storage system;

FIG. 17 is a top plan view of the suspended utensil storage system; and,

FIG. 18 is a bottom plan view of the suspended utensil storage system.
